LOOM HARNESS

John Jacob Kaufmann, Elkins Park, Pa., assignor to Steel Heddle Manufacturing Company, Philadelphia, Pa., a corporation of Pennsylvania

Application September 24, 1945, Serial No. 618,119

5 Claims. (Cl. 139—92)

1

This invention relates to loom harness, and it relates more particularly to the heddles employed in harness of the type used in installations where the warp ends are entered or inserted through the harness by means of the automatic drawing-in machines which are now in more or less common use in textile mills.

One of the most popular forms of heddles, for use in installations as aforesaid, comprise those shown in Figs. 2 and 3 of my previous Letters Patent No. 2,047,511, dated July 14, 1936. However, one difficulty which has developed in connection with the manufacture and use of such heddles arises out of the fact that in the plating of the heddles, to render the same rust proof, it frequently happens that the broad areas adjacent the slots at the ends, and adjacent the warp eyes in the center, are not properly plated, by reason of the heddles bearing against each other and thereby preventing access of the plating fluid to these areas, with the result that subsequently the heddles become rusted at these points which, of course, as is well known, causes damage to the goods being woven, and also interferes with the proper functioning of the heddles when the shedding takes place.

The principal object, therefore, of the present invention is to provide simple and efficient means on the heddles which will effectively prevent the heddles from bearing against each other where broad areas occur, and thereby insure even and complete plating of the heddles over their entire surfaces.

A further object of the invention is to provide heddles of the character aforesaid, and particularly of the type intended for use in installations using modern forms of automatic drawing-in-machines, which heddles are so constructed and arranged as to prevent distortion of the heddles through the pressure of the follower block of the drawing-in-machine during the entering operation.

The nature and characteristic features of the invention will be more readily understood from the following description, taken in connection with the accompanying drawing forming part hereof, in which:

Figure 1 is a front elevation of a plurality of heddles embodying the main features of the present invention, the same being shown mounted on fragmentary lengths of supporting rods;

Fig. 2 is a side elevation thereof, the supporting rods being shown in section;

Fig. 3 is a view similar to Fig. 2, but illustrating the heddles of this type it is also usually neces-

2

ing the form of the heddle next adjacent that shown in Fig. 2;

Fig. 4 is a view similar to Fig. 1, but illustrating a modified form of heddle construction;

5 Fig. 5 is a view similar to Fig. 2, illustrating the modified form of heddle shown in Fig. 4; and

Fig. 6 is a view similar to Fig. 3, but illustrating the form of the heddle next adjacent that shown in Fig. 5.

10 It should, of course, be understood that the description and drawing herein are illustrative merely, and that various changes and modifications may be made in the structure disclosed without departing from the spirit of the invention.

15 Referring to the drawing, in the particular embodiment of the invention therein shown, 10 and 11 are the usual heddle supporting rods which, as is well known to those familiar with 20 this art, may be supported, in any suitable manner, in frames of any preferred construction.

The heddles 12 are preferably made from thin 25 flat strips of metal initially of a uniform width corresponding to the widest portions of the heddle. The central portion 13 of each heddle 12 is preferably left the full width of the strip as is also each end portion 14 thereof, but the parts 30 of the heddles between the central portion 13, and the respective end portions 14, are sheared down to a considerably narrower width, as at 15, to afford the requisite flexibility in the heddles to permit the proper manipulation of the heddles during the entering of the warp.

The central portion 13 of the heddle is provided with the usual punched warp eye 16, the shanks of which may, if desired, be formed, in bowed conformation, out of the main plane of the heddle proper.

The central portion 13 is usually left the full 40 width of the strip, for a greater length than would be required merely for the warp eye, in order to permit the punching, above the warp eye 16, of a keyhole slot 17, which is provided when the warp is to be entered by means of a warp 45 drawing-in-machine.

Each alternate heddle of a set will ordinarily have the narrow portion of the keyhole slot 17 extending upwardly, while in the other alternate heddles the keyhole slot 17, will be punched with 50 the narrow portion extending downwardly, as is shown respectively in Figs. 2 and 3 of the drawing, this arrangement being provided to assist in the functioning of certain parts of the drawing-in machine.

Fig. 3 is a view similar to Fig. 2, but illustrating the heddles of this type it is also usually neces-

sary to leave the central portion of the heddle, below the warp eye 16, the full width of the strip, whereby the same may be engaged by parts of the mechanism of the drawing-in machine, which are used for twisting the heddle, to enable the needle of the drawing-in machine to pass freely through the warp eye 16.

Each of the end portions 14, of each of the heddles shown in the drawing (which as hereinabove mentioned are left the full width of the strip from which the heddle is formed) is punched out to provide a slot 18 for mounting the heddles 12 on the rods 10 and 11, and one side portion thereof is cut away as at 19, substantially midway the extension of the slot 18, so that when the heddles 12 are slid sidewise on the rods 10 and 11, they will pass freely without being obstructed by the bracket members (not shown) which are customarily employed for supporting the heddle rods 10 and 11 intermediate their ends.

It will be noted that in heddles of the type above mentioned, there will be broad areas 20 adjacent the end slots 18, and other broad areas 21 and 22 at the central portion of the heddle which, by reason of their relatively large width, whenever the heddles are left in their flat condition, and close to each other, will serve to prevent access of the plating fluid to these areas, so that the same will be left unplated and subsequently will become rusted while in use. The objection to heddles having rusted portions contacting the warp is too well known to need any discussion.

Heretofore various attempts have been made to overcome this difficulty by the utilization of arrangements such as are shown in the Hathaway patent, No. 1,246,002, and in my previous patent, No. 1,970,175, but these were not practical for the present purpose, by reason of the fact that when the bank of heddles in a frame was subjected to the pressure of the follower block of the drawing-in machine, during the entering of the warp, the heddles would become distorted and bent out of their normal positions, and this resulted in substantial interference with the functioning of the selector mechanism of the drawing-in machine, with resulting errors in the entering and sometimes damage to the harness and the machine.

The present invention contemplates a novel arrangement of spacer offsets formed in the narrow portions 15 of the heddles 12 which offsets, in accordance with the present invention, are provided in pairs in each heddle but at locations quite different from those of prior arrangements.

The preferred form of spacing devices used comprise the formation, in the narrow part 13 of each heddle 12, at the desired locations, of sinuous portions 23 providing extensions on each face of each heddle, which in each location are provided in alternate heddles opposite straight portions in the other alternate heddles. However, other forms of spacer offsets may be employed, of different shapes or deformations of the narrow portions of the heddles, at the desired locations.

In the construction and arrangement shown in Figs. 1, 2 and 3 of the drawing, each alternate heddle is provided, at its lower portion with a pair of off-sets 23, one set being disposed adjacent the lower widened portion 14, and the other set being disposed adjacent the widened central portion 13 of each of said heddles, whereas, in the other alternate heddles similar offsets are provided in the upper portions, and in each of said heddles one offset 23 is disposed adjacent the

upper enlarged end portion 14 in which the slot 19 is provided, and the other offset 23 is located adjacent the enlarged central portion 14.

In the form of the invention shown in Figs. 4, 5, and 6 of the drawing, the offsets 23, in each alternate heddle are provided, one at the upper end adjacent the enlarged portion 14 in which the eye 19 is located, and the other in the lower portion of the heddle just below the enlarged central portion 13 thereof, whereas each of the other alternate heddles has an offset in the upper portion, located adjacent the enlarged central portions 13 thereof, and in the lower portion is provided with an offset 23 adjacent the enlarged portion 14 at the lower end thereof in which the eye 19 is located.

It should be, of course, noted that in each instance, wherever an offset 23, in a particular heddle, is positioned, the alternate heddles on each side thereof are, at the same longitudinal location, provided with straight portions against which the offsets 23 bear when pressure is imparted by the follower block during the entering operation.

It will be noted that in each of the foregoing arrangements there is provided a set of offsets 23 immediately above and immediately below the enlarged central portions 13 of the heddles, and that these offsets are positioned well within the shed lines during the weaving operation. Heretofore it has always been thought that the provision of such spacers at such locations would seriously interfere with the formation of the shed and would result in the breaking of the warp, but it has been found in practice that such offsets may be employed without the results heretofore feared.

By the use of the offsets in the sets thereof which are provided adjacent the enlarged central portions of the heddles, there results a construction and arrangement which not only permits the plating fluid to have access to all surfaces of the heddles during the plating operation, but in the subsequent use of the heddles in connection with a warp drawing-in machine the distortion which would otherwise be caused by the pressure of the follower block of the drawing-in machine is eliminated and the proper functioning of the drawing-in machine is assured.

I claim:

1. In loom harness, a plurality of heddles made of thin flat strips of metal having portions with surfaces of relatively broad areas, the means for spacing said heddles on their supporting rods comprising the provision of sets of offsets in the heddles, one set of said offsets being disposed near the tops of the heddles, another set of said offsets being disposed near the bottoms of the heddles, another set of said offsets being disposed above and adjacent the central portions of the heddles, and another set of said offsets being disposed below and adjacent the central portions of the heddles, the offsets in each set being disposed in alternate heddles, and the heddles intermediate said alternate heddles being provided with straight portions opposite the offsets in the alternate heddles.

2. In loom harness, a plurality of heddles made of thin flat strips of metal having intermediate portions narrowed in width to provide flexibility, and other wider portions at the top and bottom and at the center with surfaces of relatively broad areas, the means for spacing said heddles on their supporting rods comprising the provision of sets of offsets in the heddles, one set of said

offsets being disposed adjacent the widened portions at the tops of the heddles, another set of said offsets being disposed adjacent the widened portions at the bottoms of the heddles, another set of said offsets being disposed above and adjacent the widened portions at the centers of the heddles, and another set of said offsets being disposed below and adjacent the widened portions at the centers of the heddles, the offsets in each set being disposed in alternate heddles, and the heddles intermediate said alternate heddles being provided with straight portions opposite the offsets in the alternate heddles.

3. In loom harness, a plurality of heddles made of thin flat strips of metal having intermediate portions narrowed in width to provide flexibility, and other wider portions at the top and bottom and at the center with surfaces of relatively broad areas, the means for spacing said heddles on their supporting rods comprising the provision of sets of offsets in the narrowed portions of the heddles, one set of said offsets being disposed adjacent the widened portions at the tops of the heddles, another set of said offsets being disposed adjacent the widened portions at the bottoms of the heddles, another set of said offsets being disposed above and adjacent the widened portions at the centers of the heddles, and another set of said offsets being disposed below and adjacent the widened portions at the centers of the heddles, the offsets in each set being disposed in alternate heddles, and the heddles intermediate said alternate heddles being provided with straight portions opposite the offsets in the alternate heddles.

4. In loom harness, a plurality of heddles made of thin flat strips of metal having intermediate portions narrowed in width to provide flexibility, and other wider portions at the top and bottom and at the center with surfaces of relatively broad areas, the means for spacing said heddles on their supporting rods comprising the provision of sets of offsets in the narrowed portions of the heddles, one set of said offsets being disposed adjacent the widened portions at the tops of the heddles, another set of said offsets being disposed adjacent the widened portions at the bottoms of the heddles, another set of said offsets being disposed above and adjacent the widened portions at the centers of the heddles, and another set of said offsets being disposed below and adjacent the widened portions at the centers of the heddles, the offsets in each set being disposed in alternate heddles, and the heddles intermediate said alternate heddles being provided with straight portions opposite the offsets in the alternate heddles,

another set of said offsets being disposed below and adjacent the widened portions at the centers of the heddles, said offsets in each instance comprising a portion of the heddle strip extending out of the main plane of the heddle on each face thereof, the offsets in each set being disposed in alternate heddles, and the heddles intermediate said alternate heddles being provided with straight portions opposite the offsets in the alternate heddles.

5. In loom harness, a plurality of heddles made of thin flat strips of metal having intermediate portions narrowed in width to provide flexibility, and other wider portions at the top and bottom and at the center with surfaces of relatively broad areas, the means for spacing said heddles on their supporting rods comprising the provision of sets of offsets in the narrowed portions of the heddles, one set of said offsets being disposed adjacent the widened portions at the tops of the heddles, another set of said offsets being disposed adjacent the widened portions at the bottoms of the heddles, another set of said offsets being disposed above and adjacent the widened portions at the centers of the heddles, and another set of said offsets being disposed below and adjacent the widened portions at the centers of the heddles, said offsets in each instance comprising a portion of the heddle strip bent in sinuous form out of the main plane of the heddle on each face thereof, the offsets in each set being disposed in alternate heddles, and the heddles intermediate said alternate heddles being provided with straight portions opposite the offsets in the alternate heddles.
